UNITED STATES PATENT OFFICE.

ISAAC STROUSE, OF NEW HAVEN, CONNECTICUT, ASSIGNOR TO LOUIS SCHIELE & CO., OF NEW YORK, N. Y.

CORSET.

SPECIFICATION forming part of Letters Patent No. 274,405, dated March 20, 1883.

Application filed December 26, 1882. (No model.)

To all whom it may concern:

Be it known that I, ISAAC STROUSE, of New Haven, in the county of New Haven and State of Connecticut, have invented a new Improvement in Corsets; and I do hereby declare the following, when taken in connection with accompanying drawings and the letters of reference marked thereon, to be a full, clear, and exact description of the same, and which said drawings constitute part of this specification, and represent, in—

Figure 1, a rear view; Fig. 2, the three back-stays detached.

This invention relates to an improvement in that class of corsets which are designed with special reference to a spinal support. In order to properly support the back, broad and heavy stays or springs are essential. If these stays are made sufficiently broad and straight, they do not readily conform to the shape of the body at the right and left of the spine. If the stays are straight, they cannot conform to the shape of the body so as to follow up onto the shoulder. The central stay, if of equal width throughout, either is too strong at the waist and downward, or too weak above, according as the stay is wider or narrower, the strongest support being necessary above the shoulder-line. The object of this invention is to construct a corset to avoid these difficulties; and it consists in a corset having a back made as a whole—that is, from the vertical shoulder-line of one side to the vertical shoulder-line of the other side, its two edges connected to the adjacent or hip sections of the corset by lacings, the back provided with a central or spinal stay, gradually expanding from the bottom end upward to the top, and a stay at each side, curved upward and forward and downward and forward from the waist-line downward, and also from the waist-line upward, the curvature of the stays conforming to the shape of the wearer, and as more fully hereinafter described.

A represents one hip-section, and B the other. The hip-sections and the front section may be of any of the usual constructions, immaterial to this invention. G is the back-section. The corresponding edges of the back-sec-

tion and the two hip-sections are provided with 50 eyelets, so that the sections may be laced together in substantially the usual manner of lacing back-sections to the sides.

The three back-stays D, E, and F are shown detached in Fig. 2. The central or spinal stay 55 is made usually about one inch wide at the lower end, and gradually expands to, say, twice that width at the upper end. The side stays E, F, are cut on a curve, as shown, and preferably of equal width throughout, usually 60 about one inch and one-eighth. The back-section is made in three parts, G, H, and I. G, the central part, conforms substantially to the shape of the central stay, D. It is made from double fabric, and forms a pocket for the 65 stay D, broken lines indicating the stay in that part G. The two parts H I are united to the part G, preferably from the waist upward and downward, extending about two-thirds the length of the corset, leaving a space, a, at the 70 top and bottom between the central part, G, and the parts H I, with an elastic connection, b, across the space between the parts. The parts H I are also made double and stitched to form a pocket for the stays E F, that pocket 75 curving corresponding to the stays—that is, upward and forward and downward and forward from the waist-line. Broken lines in the parts H I indicate the shape and position of the stays when in place. When the corset is 80 upon the person the central stay, G, lies upon the spine, and because of its broad upper end or gradually-increasing width from the lower end upward, a firm support is given to the back stronger at the top than at the waist- 85 line. The two side stays, E F, curve from the waist-line upward onto the shoulders, and downward toward the hips, thus giving a support to the shoulders, and aiding in the back-support. 90

I do not claim, broadly, a corset having a back provided with stays or busks and laced at its edges to the adjacent hip-sections. Neither do I claim, broadly, a corset-stay increasing in width from one end to the other, as such, I am 95 aware, is not new; but

What I do claim is—

A corset having a back-section laced to the

adjacent hip-sections, the said back-section provided with a central stay, D, gradually increasing in width from the bottom to the top, combined with the two stays E F, arranged respectively in the back at the left and right of the central or back stay, D, the said stays curved from the waist-line upward and for-

ward and downward and forward, substantially as shown and described.

ISAAC STROUSE,
